MILL PICK

Thomas A. Teate, Thomasville, Ga., assignor of
one-half to C. W. Kirby, Thomasville, Ga.

Application September 19, 1933, Serial No. 690,135

1 Claim. (Cl. 306—42)

The device forming the subject matter of this application is a mill pick, adapted to be used for dressing mill stones.

The invention aims to provide a device of the class described in which the peens or tools may be readily removed for sharpening or repair, or be renewed, upon occasion. A further object of the invention is to provide a device of the class described in which the chisel peen or tool may be positioned with respect to the handle of the tool in such a way that the operator can work conveniently on the stone.

It is within the province of the disclosure to improve generally and to enhance the utility of devices of that type to which the invention appertains.

With the above and other objects in view, which will appear as the description proceeds, the invention resides in the combination and arrangement 20 of parts and in the details of construction herein-after described and claimed, it being understood that changes in the precise embodiment of the invention herein disclosed, may be made within the scope of what is claimed, without departing from 25 the spirit of the invention.

In the accompanying drawing:

Fig. 1 shows in top plan, a device constructed in accordance with the invention;

Fig. 2 is a side elevation, wherein parts are 30 broken away;

Fig. 3 is a longitudinal section, parts remaining in elevation.

In carrying out the invention, there is provided a head 1, which may be made of any suitable 35 metal. If desired, the head 1 may be grooved circumferentially, as shown at 2, to form an intermediate body 3 and end members 4. The body 3 has a transverse eye 5 in which one end of the handle 6 is secured, the handle 6 being of any desired length. The end members 4 of the head 1 are supplied in their extremities with central, longitudinal bores 7, which, preferably, are cylindrical. These bores 7 are adapted to receive the 40 cylindrical shanks 8 of detachable or renewable 45 peens 9 and 10. Set screws 11 are threaded transversely into the end members 4 of the head 1, and project outwardly in an opposite direction to the handle 6. The inner ends of the set screws or securing devices 11 are adapted to be received, in 50 clamping relation, in circumferential seats 12, formed in the shanks 8 of the peens 9 and 10.

The peen 10 is pointed, as shown at 14, but the peen 9 has a chisel edge 15, disposed, preferably, at right angles to the axis of the head 1. Shoulders 16 are formed at the places where the peens

9 and 10 join their shanks 8, and the shoulders 16 engage the opposite ends of the head 1 to take the thrust when the tool is in use. If desired, the inner ends of the shanks 8 of the peens 9 and 10 may engage the head 1 at the inner ends 60 of the bores 7, as shown at 17. The construction is such that all strain is taken off the set screws or securing devices 11, when the tool is in use, and there is no chance that the set screws will be bent, so that they will be difficult to operate. 65

It is obvious that either of the peens 9 and 10 may be taken out for sharpening or repair, and that other peens may be substituted for those shown in the drawing.

Attention is directed to the fact that the peen 70 9, which has the chisel edge 15, may be adjusted axially, the shank 8 of the peen 9 turning in the corresponding bore 7. When the desired adjustment has been acquired, the corresponding set screw 11 may be tightened up, to prevent the 75 peen from turning further. It is therefore possible to adjust the chisel edge 15 of the peen 9, with respect to the handle 6, in such a way that the tool may be used conveniently by the operator, due regard being had to the angle which 80 the chisel edge 15 shall take with respect to the work. The peens 9 and 10, of course, are made of a high grade of tool steel, or similar material, and are well adapted to withstand the severe 85 use to which they are put.

Having thus described the invention, what is 85 claimed is:

A mill pick comprising a head having smooth, continuous, cylindrical, longitudinal bores in its ends, a handle connected to the intermediate portion of the head and disposed at right angles to the head, peens having cylindrical shanks detachably mounted in the bores, one peen having a chisel edge, and that peen being rotatable to change the angle between its chisel edge and the 90 handle, and set screws threaded into the head and engaging the shanks of the peens, the set screws projecting from the head in a direction substantially opposite to the handle, said peen and the head having cooperating parts that abut 95 in positive thrust-resisting relation, independently of the corresponding set screw and the handle, when said peen is in use; and regardless of the degree to which it may have been rotated.
